ATTORNEY

UNITED STATES PATENT OFFICE.

WILLIAM G. KENDALL, OF NEWARK, NEW JERSEY.

COMPACT HOLDER AND EJECTOR FOR VANITY CASES.

Application filed December 22, 1926. Serial No. 156,479.

This invention relates to vanity cases and particularly to an improved compact holder and ejector for vanity cases and has for an object to provide an improved structure 5 wherein the compact is held in place against accidental removal, but in position to be easily and quickly ejected.

Another object of the invention is to provide an improved compact holder and ejector 10 wherein the ejector is arranged with one leg beneath the holder and the other above or adjacent the holder and in a position to be swung for causing a loosening or ejecting of the compact holder.

15 A further object of the invention is to provide a compact holder and ejector wherein the holding and ejecting members are mounted on or carried by an inserted ring in the vanity case.

20 In the accompanying drawing—

Figure 1 is a top plan view of a vanity case with a compact holder and ejector embodying the invention shown applied thereto.

Figure 2 is an enlarged sectional view 25 through Figure 1 on line 2—2.

Figure 3 is a view similar to Figure 1 but showing the ejector in an operated position.

Figure 4 is a detail fragmentary perspective view showing part of a case, ejector and 30 holding members.

Figure 5 is a fragmentary sectional view similar to the upper half of Figure 2 but showing a modified construction.

Figure 6 is a view similar to Figure 2 but 35 showing a modified form of the invention.

Figure 7 is a sectional view through Figure 6 on line 7—7, the same being on an enlarged scale.

Figure 8 is a view similar to Figure 6 but 40 showing a further modified form of the invention.

Figure 9 is a sectional view on an enlarged scale through Figure 8, the same being taken on line 9—9.

45 Figure 10 is a detail perspective view of the ejector shown in Figure 1.

Referring to the accompanying drawing by numerals, 1 indicates the body of a vanity case and 2 the lid hingedly connected therewith. The body 1 is provided with a bead 3, which on the inner part, carries the wire ring 4, part of which acts as a pintle for the hinge 5 and certain bent parts 6 of ring 4 act as holding members for the compact holding ring 7. The holding ring 7 as shown in Figure 4, is preferably made L-

shaped in cross section and is provided with a number of pressed up resilient portions 8 arranged at a proper height to slightly overlap the compact plate 9. of the compact 10. 60 These members act to hold the compact in the body 1 while the ejector 11 may function to eject the compact as shown in Figure 3 whenever the arm 12 is raised. It will be noted that the arm 13 is always beneath the compact plate 9 so that by raising arm 12, the compact plate will be forced past certain of the holding burs or projections 8 and thereby the compact will be released.

The holding ring 7 is provided with an 65 inwardly bent section or portion 14 which provides an opening through which the part 15 of ejector 11 projects. Also by pressing back the comparatively short section 14, the pintles 15' and 15" may be readily inserted 70 as indicated particularly in Figure 4 whereby the ejector is pivotally mounted on the ring 7. The pintles 15' and 15" may be inserted in any desired manner preferably by 75 having one of these pintles bent down and then the other pintle inserted and finally the bent one inserted and bent back into its original position as shown in Figure 11.

In Figure 5, a slightly modified structure 80 is shown to that illustrated in Figures 1 to 3. The modification consists of having the arm 12' bent back over the top section 16 of ring 7. By forming the arm 12' in this manner, instead of pulling upwardly on this arm for ejecting purposes, the arm must be 85 pressed downwardly whereupon arm 13 will be raised upwardly to produce an ejecting action similar to that shown in Figure 3. Where the ejector is constructed as shown in Figures 1 to 3, arm 12 extends slightly over 90 the compact 10 and may act as a holding member for the powder puff 17. In the form shown in Figure 5, the arm 12' is out of the way and does not interfere in any way with the use of the powder or of rapidly moving 100 the powder puff over the compact in any desired manner.

Figures 6 and 7 show a modified form of 105 the invention wherein a differently formed casing 1' is provided. Casing 1' is provided with a lid 2' hingedly connected with casing 1' and formed to fit over the offset portion 18. This portion is pressed inwardly from the side walls 19 and forms an interior shoulder 20 which is adapted to receive one or 110 more pressed out tongues 21 pressed from the compact supporting ring 22. This ring

is preferably channel-shaped in cross section and also preferably provided with several tongues 21 which snap beneath the shoulder 20 when the ring is placed in position. The 5 inner part of ring 22 is provided with any desired number of lugs or pressed out portions 8' which function in a similar manner to portions 8 of the preferred form. The 10 ejector 23 is identical with that shown in Figure 3 and functions in the same manner so that no additional description will be necessary.

In Figures 8 and 9 a further modified form of the invention is shown wherein the 15 ring 24 is somewhat similar to the ring 16 of the preferred form but is provided with a pressed down and radially extending portion 25 adapted to fit under the inwardly extending flange 26 of the casing 1". The 20 ring 24 is provided with any desired number of resilient looped portions 27, there being shown in the drawing two of these looped portions, though a different number may be used if desired. When the compact plate 28 25 is forced downwardly into the casing 1", it snaps past these resilient holding members 27 whereby the compact is held against accidental removal. An ejector 29 is provided similar in construction to that shown in the 30 other forms of the invention.

In most forms of the invention, a substantially U-shaped ejector is provided and one that is pivotally mounted with one leg projecting beneath the compact and the other 35 leg to some point convenient for operation whereby the leg beneath the compact may be swung and act in a certain sense as a lever or cam for crowding the compact past the retaining lugs which are more or less resilient 40 and thereby allow this action as well as allow the compact to be snapped properly into position.

What I claim is:

1. A compact holder and ejector for vanity 45 cases comprising a holding ring, a retaining ring formed with means for holding said compact holding ring in place, means on the compact holding ring for holding a compact in the case, and a pivotally mounted ejector 50 carried by said compact-holding ring having one section projecting beneath the compact carried by the vanity case and the other section projecting to a point readily accessible.

2. A compact holder and ejector for vanity 55 cases comprising a compact holding ring formed with resilient pressed portions adapted to snap over the upper edge of the compact plate when the same is forced into the case, said ring being formed with a notch 60 and a swingable ejector having a pair of ears extending beneath said ring through said notch, one arm extending beneath the compact plate and a second arm above the compact plate. 65

3. A compact holder and ejector for vanity cases comprising a ring adapted to be mounted in the body of a vanity case, an ejector formed with a substantially U-shaped body member having a pair of arms and a 70 pair of ears extending through said ring for pivotally mounting the ejector, and means carried by the ring for disengageably holding the compact in the case within the ring, said ejector being positioned with one of 75 said arms normally beneath said compact whereby when the other arm is manually actuated the compact will be forced past said holding means and thereby be released.

4. A compact holder and ejector for vanity 80 cases comprising a substantially L-shaped ring adapted to be fitted into the body of a vanity case, said ring being formed with a plurality of pressed out members for holding a compact in said body, said ring having an 85 opening therein, and an ejector having a looped portion pivotally mounted within the ring and a pair of arms extending from the looped portion through the opening, one of 90 said arms being normally positioned beneath said compact and the other at a point above the compact.

5. The combination with a vanity case 95 provided with a body and a substantially annular ring carried by the body and formed with bent portions, of a compact holder comprising a holding ring adapted to be held in the body by said bent portions, said holding ring being formed with compact holding 100 means for holding the compact in the body, and an ejector having integral pintle members, loosely interlocking with said holding ring for pivotally mounting the ejector, said ejector having two arms, one projecting beneath said compact and the other projecting to a point convenient of manual actuation. 105

WILLIAM G. KENDALL.
